(57) **CLAIM**

The ornamental design for a carpet protector, as shown and described.

DESCRIPTION

FIG. 1 is a top, front, right side perspective view of the carpet protector of the present invention;

FIG. 2 is a reduced scale top, front, right side view in use of the carpet protector of FIG. 1;

FIG. 3 is an enlarged front elevational view of the carpet protector of FIG. 1, the rear view being a mirror image thereof;

FIG. 4 is a left side elevational view of the carpet protector of FIG. 1, the right view being a mirror image thereof;

FIG. 5 is a top plan view of the carpet protector of FIG. 1; and,

FIG. 6 is a bottom plan view of the carpet protector of FIG. 1.

The broken lines showing of a file cabinet in FIG. 2 is for illustrative purposes only and forms no part of the claimed design.
